UNITED STATES PATENT OFFICE.

ALEXANDER FLEMING, OF ORLEANS, IOWA.

WASHING-MACHINE.

SPECIFICATION forming part of Letters Patent No. 243,878, dated July 5, 1881.

Application filed April 30, 1881. (Model.)

To all whom it may concern:

Be it known that I, ALEXANDER FLEMING, of Orleans, in the county of Appanoose and State of Iowa, have invented a new Improvement in Washing-Machines, of which the following is a full, clear, and exact description.

My invention relates to a machine for washing clothes by pumping or forcing water through them.

10 In the accompanying drawings, Figure 1 is a longitudinal vertical sectional view of an apparatus embodying my improvements. Fig. 2 is a top view of the water-tank, clothes-receptacle, and follower. Fig. 3 is a bottom view 15 of the piston or plunger.

The various parts of the apparatus may be made of wood, zinc, galvanized iron, or any other suitable material, and the general form of the tub or tank and the parts held by it 20 may be angular or of any other desired shape.

A represents a tank or tub for holding water.

B is the clothes-receptacle, consisting of a box provided with perforations b in its bottom. 25 It is provided with short feet a, which rest in the bottom of the tank A, and it is prevented from moving longitudinally or laterally by means of angle-posts a², attached to the bottom of the tank and engaging with the corners of 30 the box.

C is a follower, consisting of a skeleton-plate or a frame-work. It is placed over the clothes in the box B, and is held in place by means of chains D, each of which has its lower end secured to the bottom of the box B and its upper portion arranged to engage with pins e on the top of the follower.

F is a piston or plunger, working in the box B above the follower. It is provided with an 40 upwardly-extending rod or stem, g, to the upper end of which is pivoted a hand-lever, H, having its fulcrum in or on a standard, J, carried by the box B.

The tank or tub A is supplied with a suitable

quantity of water. The box or clothes receptacle B being in position in the tub or tank, the clothes to be washed are placed in the box and spread out over its perforated bottom. The follower C is then placed over the clothes and held down by the chains D, hooked over the pins or studs e. The piston or plunger F is then placed in the box above the follower and the lever H adjusted to the rod or stem g. The clothes are cleansed by working the piston or plunger up and down by means of the lever, which operation alternately sucks or pumps the water up and forces it down through the clothes and through the perforations in the box and the skeleton-follower resting over them, so as to extract the dirt and force it out of the clothes by the currents of water passing through them.

Having thus described my invention, what I claim as new, and desire to secure by Letters Patent, is—

1. An apparatus for washing clothes by forcing water through them, consisting of a water tank or tub, a perforated box or clothes receptacle resting in said tank, a skeleton-follower for holding down the clothes, and a piston or plunger working above the follower and provided with means for operating it, substantially as and for the purposes herein shown and described. 65

2. The combination, with the clothes-receptacle B, of the skeleton-follower C, provided with the pins e, and the chains D, engaging with said pins, substantially as and for the purpose herein described. 75

3. The combination, with the perforated clothes-receptacle B and the skeleton-follower C, of the piston or plunger F, provided with the rod or stem g, and the hand-lever H for operating said piston or plunger, substantially as herein described. 80

ALEXANDER FLEMING.
